UNITED STATES PATENT OFFICE.

JOHN C. LIGHTHOUSE, OF ROCHESTER, NEW YORK.

MAIL-BAG.

SPECIFICATION forming part of Letters Patent No. 374,844, dated December 13, 1887,

Application filed September 19, 1887. Serial No. 250,134. (No model.)

To all whom it may concern:

Be it known that I, JOHN C. LIGHTHOUSE, of Rochester, in the county of Monroe and State of New York, have invented a certain 5 new and useful Improvement in Mail-Bags; and I do hereby declare that the following is a full, clear, and exact description of the same, reference being had to the drawings accompanying this application.

10 My improvement relates to that class of mail bags and pouches in which the mouth is composed of metallic bars jointed or hinged at the quarters, so as to be opened in square form. Such devices are already known, and 15 I do not claim the same, broadly.

My invention consists in the combination, with such a device, of two locking-straps hinged together and applied to the front bars, and so arranged, as hereinafter described, that 20 when drawn endwise to lock the bag the hinge of the locking-straps comes on one side of the hinge of the mouth-bars, as hereinafter more fully described.

In the drawings, Figure 1 is a side elevation 25 of the mouth of a mail-bag in the locked position, exhibiting my invention. Fig. 2 is a plan view of the same unlocked and partially opened. Fig. 3 is an enlarged side elevation of a portion of the same. Fig. 4 is a vertical 30 cross-section in line $x x$ of Fig. 3. Fig. 5 is a plan view of the mouth fully opened. Fig. 6 is a vertical cross-section similar to Fig. 4, but showing a modification. Figs. 7 and 8 are elevations of the hinged locking-straps, showing 35 modifications in the means for fastening the mouth of the bag.

A indicates the leather bag, which is of usual form and construction.

My improvement is as follows:

40 B B and B' B' are four side straps or plates, which constitute the mouth of the bag. The bag is secured to the bottom edge of these straps by ordinary rivets, a a, the lower edges of the straps being offset or shouldered, as 45 shown at d d, so as to give room for the leather inside when the mouth is closed. The side straps are pivoted or hinged at the four quarters, as shown at c c c c, two of the hinges coming at the edges and two in the center of 50 the width of the bag. By this means the mouth of the bag can be closed tightly in flat

condition to close the bag, or can be extended wide open, as shown in Fig. 5, for assorting mail. When so opened, the side straps constitute a square. Fig. 2 shows the bag partially 55 open. The straps B B on two sides of the bag have right-angled flanges b b at the top, which cover the edges of the other two straps, B' B', when the bag is closed, thereby preventing the entrance of any instrument for opening 60 the bag.

C are two sliding locking-straps hinged together centrally at f, and lying flatwise against the two front side straps B' B', being held to place by rivets g g, that pass through 65 slots h h of the locking-straps. By this means the locking-straps have end movement to a limited degree. The locking-straps have right-angled open slots i i and projecting tongues k k, and the two rear side straps B' B' have 70 staples l l, that coincide with the slots. When the bag is closed, the staples l l pass through openings in the front side straps B' B' and through the slots i i of the locking-straps, and then by sliding the locking-straps to the left 75 the tongues k k pass through the staples and lock the parts firmly together. When the straps are so thrown to lock the bag, the hinge f of the locking-straps comes to one side of and out of line with the hinge c of the side 80 straps, thereby stiffening the mouth of the bag and removing a portion of the strain from the fastenings. When the sliding straps are thrown back to unlock the bag, the hinge f coincides with the hinge c of the side straps, 85 and the bag can then be opened without trouble.

Instead of the open slots i i of the locking-straps, closed slots such as shown in Figs. 7 and 8 may be used, and instead of the staples 90 l l T-headed nails such as shown in Figs. 6 and 7 may be employed.

D is the tag or label holder, the same consisting of a plate hinged or jointed to the end of one of the locking-straps C, its outer end 95 passing over a staple, m, reaching through the front side straps and secured by a suitable lock, n. This holds the locking-straps in the locked position, and they can be moved back only by removing the lock.

p p are straps or loops by which the bag can be hung up while being filled.

The mail-bag above described is more convenient and effective in use than common mail-bags, as the mouth is held wide open when assorting. It can be closed and locked quicker than can be done by the common leather strap, and when locked it is more secure, as there are no leather straps that can be cut.

Having described my invention, I do not claim, simply and broadly, hinged bars or plates forming the mouth of a mail-bag; nor do I claim, broadly, a sliding locking-strap.

What I claim, and desire to secure by Letters Patent, is—

In a mail-bag, the combination of the side

straps, B B and B' B', hinged at *c c*, forming the mouth of the bag, and the locking-straps C C', hinged at *f* and fitted to the front of the side straps, the hinge of the locking-straps being thrown past the hinge of the side straps when 20 the parts are locked, said parts being provided with suitable fastening devices, as described. *

In witness whereof I have hereunto signed my name in the presence of two subscribing 25 witnesses.

J C. LIGHTHOUSE.
